CONDUCTOR GUIDE IN INSULATING MACHINE

Waldemar C. Ewaldson, Millington, N. J., assignor
to Western Electric Company, Incorporated,
New York, N. Y., a corporation of New York

Application April 16, 1947, Serial No. 741,921

3 Claims. (Cl. 92—55)

1

This invention relates to conductor guides in insulating machines, and more particularly to guides for a plurality of electrical conductors in a pulp insulating machine.

Pulp insulating machines have been employed to insulate large groups of wires simultaneously as they are advanced longitudinally with a Fourdrinier wire to which pulpos material is continuously applied. The uniform formation of the insulating coverings on the electrical conductors depends greatly upon the accurate guiding of the conductors with respect to the plane in which the portion of the Fourdrinier wire, to which the pulp is applied, travels. The location of the plane, through which the conductors travel, with respect to the plane of the Fourdrinier wire receiving the supply pulpos material may vary depending upon the gages of the conductors in each group which are to be insulated in the machine.

An object of the invention is to provide a conductor guide in a pulp machine which is readily variable, with respect to a Fourdrinier wire to which pulp material is applied to cover the electrical conductor, with variations in the gage of the conductor.

With this and other objects in view, the invention broadly comprises a conductor guide in a pulp insulating machine having a Fourdrinier wire to which pulpos material is applied, the conductor guide including a sheave to receive an electrical conductor during its advancement longitudinally relative to the wire, a bracket to rotatably support the sheave above the wire and means to vary the position of the sheave relative to the wire to vary the position of the conductor in the pulpos material to be formed on the conductor.

More specifically, the invention includes a mechanism for guiding electrical conductors in a selected plane, in a pulp insulating machine having a driven continuous Fourdrinier wire extending around supporting rollers, as the conductors are advanced longitudinally with the upper portion of the wire between the supporting rollers and within a quantity of pulpos material continuously supplied to the said upper portion of the wire. The guiding mechanism comprises a plurality of like sheaves rotatably supported by like brackets mounted freely on a rotatable shaft having end portions with axes coincident with each other and eccentric with the central bracket supporting portion of the shaft. Spring pressed plungers are provided for the brackets to individually hold them in either operative or inoperative positions, they being effective to hold their respective brackets against rotation with the shaft when the shaft is rocked from one position to another by the aid of a hand crank to vary the positions of the sheaves simultaneously relative

2

to the wire for variations in the sizes of electrical conductors to be guided through the machine. The hand crank performs two additional functions, (1) serving as a pointer relative to a dial having indications representing the location of the crank or pointer for the different gages of electrical conductors and (2) embodying a spring pressed plunger, the leading end of which is receivable in any of a plurality of apertures in the dial adjacent the indications thereon to lock the crank at any one of these positions.

The shaft supporting the brackets with their sheaves, as well as the hand crank and the dial is in the form of a carriage movable longitudinally of the wire to vary the positions of the sheaves with respect to the inlets of channels to which the supply of pulpos material is fed for the individual electrical conductors. The carriage is positioned to ride upon spaced parallel tracks provided with teeth, in the form of a rack in each of their upper surfaces, to be engaged by pinion like ends of an adjusting rod, mounted for rotation in the carriage and by the aid of which the carriage may be adjusted longitudinally of Fourdrinier wire on its tracks and locked in adjusted position.

Other objects and advantages will be apparent from the following detailed description when considered in conjunction with the accompanying drawings, wherein

Fig. 1 is a side elevational view of a portion of a pulp insulating machine, embodying the invention, portions thereof being broken away;

Fig. 2 is an enlarged fragmentary sectional view taken along the line 2—2 of Fig. 1;

Fig. 3 is a fragmentary sectional view taken substantially along the line 3—3 of Fig. 2;

Fig. 4 is a fragmentary side elevational view of the structure shown in Fig. 2; and

Fig. 5 is an enlarged fragmentary sectional view taken along the line 5—5 of Fig. 3.

Referring now to the drawings, the control mechanism indicated generally at 10 is made a part of a pulp insulating machine which includes a Fourdrinier wire 11, of the endless type, mounted on supporting rollers 12 and 14, one or both of which are driven to cause the upper portion of the wire between the supporting rollers to travel in the direction of the arrow. Tensioning means indicated generally at 15 to create a selected variable tension in the wire is the subject matter of the applicant's copending application Serial No. 741,920, filed April 16, 1947, now Patent No. 2,475,426. Pulpos material 16 is fed continuously to the wire 11 from a supply tank 17 and through a chute 18 to the entrance ends of channels 19 formed by deckles 20 of a given height, their lower edges being disposed closely adjacent to butt out of engagement with the upper portion of the wire 11. The channels are

provided for electrical conductors 21 and individual supplies of the pulpois material 16 as they are advanced longitudinally with the upper portion of the wire 11. The conductors 21 are received from individual supplies (not shown) and directed to the unit 10 by individual guide rollers 22.

The unit 10 comprises a plurality of sheaves 25 to receive their respective conductors 21 and guide them in a given plane with respect to the upper portion of the wire 11. The sheaves are identical in structure, they being provided with central apertures 26 (Fig. 5) to receive hubs 27 carrying bearings 28 for rotation on hollow spindles 29. The spindle 29, in each sheave unit, is carried by one leg 30 of a bracket 31, the opposing leg 32 carrying a threaded element 33 which extends into the internally threaded portion of the hollow spindle 29 assisted by a set screw 34 to complete the spindle structure and to secure the sheave 25 in place. Each sheave is free to rotate on its spindle during the longitudinal advancement of its respective conductor. In the present embodiment there are thirty-two sheaves and supporting brackets identical in structure, as well as a like number of channels 19 positioned longitudinally of the upper portion of the Fourdrinier wire 11.

Each bracket 31 is provided with a central aperture 36 to receive a central portion 37 of a control shaft indicated generally at 38. A portion 39 of each bracket which surrounds the central portion 37 of the shaft 38 is of a given width whereby the sides thereof will abut the adjacent sides of the similar portions of the adjacent brackets to maintain the brackets properly positioned on the shaft leaving the shaft free to rotate in the aligned apertures 36 of the brackets. The upper portion 40 of each bracket is arcuate in general contour with outwardly projecting portions 41 and 42 serving as safety stops when any of the brackets are moved between their operative and loading positions. The projection 42 being larger than the projection 41 serves as a handle for its respective bracket to move the bracket from the operating position shown in solid lines in Fig. 3 to the loading position shown in broken lines in this figure. The bracket is moved into the loading position when a new wire is to be fed through the machine.

A spring pressed plunger 45 is provided for each bracket, these plungers being housed in a hollow lateral member 46 of a main carriage 47 of the unit 10. A helical spring 49 for each plunger 45 normally urges it downwardly to be received in either recesses 50 or 51 in the arcuate portion 40 of its respective bracket to lock the bracket either in its operating or loading position. A knurled handle 52 mounted on the upper end of each plunger enables the operator to remove the plunger from either recess 50 or 51 for movement of the bracket.

The shaft 38 has end portions 55 and 56 whose axes are aligned with each other and eccentric with respect to the axis of the central portion 37. The portions 55 and 56 of the shaft 38 are journaled in aligned bearings 57 and 58 of the carriage 47, a hand crank 59 being fixedly mounted on the outer end of the portion 56. The crank 59 carries a pointer 61 movable relative to a dial 62 which has indications 63 thereon representing the different gages of conductors which may be pulled through the machine and the location of the end of the crank for these various gages of conductors. A handle portion

65 for the crank 59 is connected to a spring pressed plunger 66 positioned to be received in any one of a plurality of recesses 67 disposed adjacent the indications 63 to lock the hand crank 5 in any selected one of the positions. Movement of the handle 65 outwardly will remove the plunger 66 from its present recess and free the crank for movement to any one of the other positions.

10 The carriage 47 which supports all of the brackets 31, together with the shaft 38, the crank 59 and the dial 62 is supported for movement on parallel rails 70, the ends of which are mounted on uprights 71 of the main frame of the machine. The upper surface of each track 70 is provided with teeth 73 in the form of a rack. An actuating element in the form of a rod 74 having pinion-like teeth 75 in each end thereof to interengage the teeth 73 of the tracks, may be rotated by the aid of a central gripping portion 77 to move the carriage toward or away from the entrance ends of the channels 19. The actuating element 74 may be locked in place by a threaded element 79 actuatable by the aid of a handle 80 and receivable in a threaded aperture 81 of the carriage 47.

When the pulp machine is being conditioned for operation and the selected set of thirty-two conductors 21 are being threaded through the machine, the sheaves 25 are in their loading position, shown in broken lines in Fig. 3, where they are held by their plungers 45. After the conductors 21 have been threaded through the machine, the sheaves are moved singly into engagement with their respective conductors and locked in their operating positions by the plungers 45 entering their recesses 50. The gage of the conductors now in the machine being known, the required adjustments are made therefor. If the machine had previously been set for 26 gage conductors and it was now receiving 22 gage conductors, the handle 65 is moved outwardly to withdraw the plunger 66 from the recess 67 adjacent the indication 63 for the 26 gage position 30 on the dial, after which the crank is moved until the pointer 61 registers with the 22 gage position 35 and the plunger enters the adjacent recess 67. The machine may now be set in operation, advancing the conductors in a given plane relative to and parallel with the plane of the upper 40 portion of the wire 11 while the pulpois material is fed to the wire.

The position of the conductors in a given plane relative to the Fourdrinier wire is important in 45 causing the formation of ribbons of the pulpois material centrally on the conductor. When the sheaves are in their correct positions for larger conductors to be positioned centrally in their 50 smaller conductors centrally of similar ribbons of material. The smaller conductors would be guided in a plane too great a distance from the Fourdrinier wire resulting in the formation of 55 ribbons which may or may not surround the smaller conductors, and if they did surround the conductors, the conductors would not be centrally positioned in the ribbons. Through the aid of this mechanism the sheaves may be accurately adjusted to simultaneously change the 60 positions of the sheaves to cause them to guide the conductors, of any of the gages, in a selected variable plane relative to the plane of the wire and centrally of the ribbons formed of the pulpois material in each channel after most of the water 65 has been removed from the material.

With certain gages of conductors, it is important for them to enter the pulpous material sooner and remain therein longer than is required for other gages of conductors in the forming of the ribbons of the material on the conductors. This is accomplished by movement of the unit 10 on its tracks 70 to move the sheaves 25 toward or away from the entrance ends of the channels 19 formed by the deckles 20. To move the carriage or unit the actuating element 74 is released by rotating the locking element 79 after which the actuating element is rotated, causing its pinion-like ends 75 to travel along the rack-like tracks 70 until the sheaves are in the desired positions. The actuating element is again locked in place.

Although specific improvements of the invention have been shown and described, it will be understood that they are but illustrative and that various modifications may be made therein without departing from the scope and spirit of this invention as defined by the appended claims.

What is claimed is:

1. A mechanism for guiding electrical conductors in a selected plane, in a pulp insulating machine having a continuous Fourdrinier wire driven on spaced supporting rollers, as the conductors are advanced longitudinally and substantially parallel with the plane of the upper portion of the wire between the supporting rollers and within a quantity of pulp continuously supplied to the said upper portion of the wire, the guiding mechanism comprising sheaves for the conductors, like brackets for rotatably supporting the sheaves having aligned apertures therein and spaced recesses positioned radially of the apertures, a shaft, with a central portion extending through the said apertures to thereby support the brackets, having aligned end portions eccentric with the central portion, aligned bearings to support the end portions of the shaft, a retaining plunger supported at a fixed position adjacent each bracket and normally urged to enter one of the recesses thereof to hold the bracket in its operating position with its sheave adjacent the wire, and also normally urged to enter the other recess to hold its bracket and sheave in a loading position away from the wire, and a crank mounted on one of the end portions of the shaft to rock the shaft into any selected one of a plurality of positions to cause the eccentric central portion of the shaft to vary the positions of the sheaves simultaneously relative to the wire.

2. A mechanism for guiding electrical conductors in a selected plane, in a pulp insulating machine having a continuous Fourdrinier wire driven on spaced supporting rollers, as the conductors are advanced longitudinally and substantially parallel with the plane of the upper portion of the wire between the supporting rollers and within a quantity of pulp continuously supplied to the said upper portion of the wire, the guiding mechanism comprising sheaves for the conductors, like brackets for rotatably supporting the sheaves having aligned apertures therein, a shaft, with a central portion extending through the said apertures to thereby support the brackets, having aligned end portions eccentric with the central portion, a carriage having aligned bearings to support the end portions of the shaft, means supported by the carriage to hold the brackets against rotation, a crank mounting on one of the end portions of the shaft to rock the

shaft into any selected one of a plurality of positions to cause the eccentric central portion of the shaft to vary the positions of the sheaves simultaneously relative to the wire, and a support for the carriage whereby the carriage may be moved relative to the upper portion of the wire in a plane parallel therewith to vary the positions of the sheaves with respect to the wire.

3. A mechanism for guiding electrical conductors in a selected plane, in a pulp insulating machine having a continuous Fourdrinier wire driven on spaced supporting rollers, as the conductors are advanced longitudinally and substantially parallel with the plane of the upper portion of the wire between the supporting rollers and within a quantity of pulp continuously supplied to the said upper portion of the wire, the guiding mechanism comprising sheaves for the conductors, like brackets for rotatably supporting the sheaves having aligned apertures therein, a shaft, with a central portion extending through the said apertures to thereby support the brackets, having aligned end portions eccentric with the central portion, a carriage having aligned bearings to support the end portions of the shaft, means supported by the carriage to hold the brackets against rotation, a crank mounted on one of the end portions of the shaft to rock the shaft into any selected one of a plurality of positions to cause the eccentric central portion of the shaft to vary the positions of the sheaves simultaneously relative to the wire, a support for the carriage whereby the carriage may be moved relative to the upper portion of the wire in a plane parallel therewith to vary the positions of the sheaves with respect to the wire, and means to move the carriage on the support.
